UNITED STATES PATENT OFFICE.

LAWRENCE P. CRECELIUS, OF CLEVELAND, OHIO.

RAIL-BOND.

1,268,328.

Specification of Letters Patent. Patented June 4, 1918.

Application filed July 24, 1916. Serial No. 110,857.

To all whom it may concern:

Be it known that I, LAWRENCE P. CRECELIUS, a citizen of the United States, residing at Cleveland, in the county of Cuyahoga and State of Ohio, have invented a certain new and useful Improvement in Rail-Bonds, of which the following is a full, clear, and exact description.

This invention relates to improvements in rail bonds and is closely related to, and covers a modification of the rail bond constituting the subject matter of my prior application filed May 3, 1916, Serial No. 95051.

16 In said application I have disclosed a rail bond as well as a process of producing the same, wherein the end or terminal of the conductor of the bond, which may be a bundle or group of wires or ribbons, is surrounded by a sleeve or terminal in such a way that on one face of the bond, that is, the face which is designed to be secured to the rail, such as by an electric brazing process, is exposed as far as the sleeve is concerned, thus permitting the individual strands, or the terminal end of the conductor itself to be brazed directly to the rail. A strip of brazing material is interposed between the rail and the exposed face of the conductor, the said strip in said application previously referred to, being at one end attached to the terminal part of the bond, and overlying the said face of the conductor which is exposed or not covered by the sleeve.

35 In said application the sleeve referred to becomes intimately or integrally attached to the terminal portion of the conductor when the bond is brazed or attached to the rail, in which time the sleeve, in accordance with the disclosures in said application, is solidly brazed to the conductor by reason of the fact that there is interposed between the sleeve and conductor an intermediate or inner brazing sleeve which is employed for the purpose of intimately attaching or uniting the sleeve to the conductor. In said application the sleeve is non-intimately attached to the conductor (in the process of producing the bond) by a bulldozer, or by any other suitable device by which the sleeve, conductor

and inner brazing sleeve can be cold pressed together.

In the present application, the inner brazing sleeve is eliminated, and the terminal sleeve is brazed or welded to the terminal portion of the conductor in the process of producing the bond rather than in the process of applying the bond to the rail, but this is accomplished in such a manner as to leave one face of the conductor exposed so that it can be brazed directly to the rail without being in any manner held away from the rail by the terminal sleeve.

My invention may be briefly summarized as consisting in certain novel details of constructions and combinations and arrangements of parts which will be described in the specification and set forth in the appended claims. In the accompanying sheet of drawing, Figure 1 is a front view, Fig. 2 is a side view, and Fig. 3 is a cross sectional view substantially along the line 3—3 of Fig. 1, showing one form of bond made in accordance with my invention; Fig. 4 is a face view, Fig. 5 is an edge or side view, and Fig. 6 is a cross sectional view along the line 6—6 of Fig. 4, showing a second form of bond made in accordance with my invention; Fig. 7 is a face view, Fig. 8 is a sectional view substantially along the line 8—8 of Fig. 7; Fig. 9 is a cross sectional view substantially along the line 9—9 of Fig. 7, showing a third form of bond made in accordance with my invention; and Fig. 10 is a cross sectional view showing a brazing strip applied to the bond.

Referring first to Figs. 1 to 3, 10 represents the conductor of a bond here shown as consisting of a group or bundle of wires. Applied to each end of the conductor 10 is a terminal sleeve 11 which is either brazed or welded to the conductor, the brazing or welding of the sleeve to the conductor and the flattening or shaping of the entire terminal end of the bond being preferably accomplished in the same operation or by the same stroke or strokes of the dies. The dies in which the brazing or welding is accomplished are so formed as to flatten the portion which is designed to be attached or

- brazed to the rail, and at the same time securely braze or weld the sleeve to such flattened portion but where the conductor emerges from the sleeve or terminal the terminal rather loosely surrounds the conductor *i. e.* is not brazed or welded to the conductor, so that the strands will not be cut or crushed at the point where they emerge from the sleeve. This sleeve is so formed that when it is applied to the conductor in the manner just explained, one face 10^a of the conductor is exposed through the sleeve so that the said face of the conductor can be brazed directly to the rail by any suitable bonding apparatus such as one or two high resistance heating electrodes which are designed to be pressed against the reverse side 10^b of the terminal, in other words, the side which is completely covered by the terminal sleeve 11.
- 20 The edge or side portions of the sleeve partially surrounding the flattened portion may terminate a short distance from the face 10^a, as is clearly shown in Fig. 3, or such edges may come up flush with said face, or they may, if desired, slightly overlap the side edges of the face 10^a of the conductor, but in any event, during the welding or brazing process by which the sleeve is applied or attached to the conductor, the edges or edge portions of the sleeve will not project beyond the flat face 10^a or otherwise prevent the conductor being brazed directly to the rail.

In brazing this bond to the rail, as well as the bonds shown in the succeeding figures, a suitable strip of brazing material 12, see Fig. 10, will be employed, which strip may be placed between the face 10^a of the bond and the rail just before the bond is brazed to the rail, or this strip or piece of brazing material may form a part of the bond, in which event it can consist of a strip or sleeve partially surrounding the terminal of the bond, and may be slipped onto the terminal, or attached thereto by any suitable means, such as by riveting.

In Figs. 4, 5 and 6 I have shown a conductor which in all material respects is like that first described, except the conductor here designated 15, is a ribbon conductor, that is, one wherein the strands are flat and are arranged face to face. The terminal sleeve here designated 16, is, as in the first described construction, welded or brazed to the terminal portion of the conductor in the process of making the bond and at the time the terminal end of the bond is shaped. At the point where the conductor emerges from the sleeve, the latter loosely but completely surrounds the conductor, but at other portions partially surrounds it so as to leave the flat exposed face of the conductor, here designated 15^a, adapted to be brazed directly to the rail.

In Figs. 7, 8 and 9 I have shown a T-shaped terminal made precisely by the method first described. In this case the conductor designated 20, has secured to its terminal portion by brazing or welding, a terminal sleeve 21 which wholly and relatively 70 loosely surrounds the strands at one point, and at other points is integrally or intimately attached to the conductor and partially surrounds the same, leaving the flat exposed face 20^a to be brazed directly to the 75 rail in the manner previously explained. Here again, as well as in the preceding figures, the edge portions of the sleeve which extend around the perimeter of the face 20^a of the conductor may be flush with said face 80 20^a, or if desired, they may slightly overlap it or terminate a short distance from the face 20^a, the latter being shown in the drawings.

As here shown, the rear face 20^b of the 85 terminal of the bond, in other words, the face which is designed to be engaged by the bonding electrode or electrodes which create the heat necessary to braze the bond to the rail is completely covered by the terminal 90 sleeve, but it is not essential that the sleeve extend from end to end of such rear face, but the complete covering of such face is deemed advisable to avoid the electrode, or electrodes gouging or cutting the strands. 95

I do not desire therefore, to be confined to the exact details shown, but aim in my claims to cover all modifications which do not involve a departure from the spirit and scope of my invention. 100

Having thus described my invention, what I claim is:

1. As an article of manufacture, a rail bond adapted to be attached to the adjoining ends of two rails, and comprising a conductor having a terminal part and a sleeve intimately attached to such terminal part, said sleeve having a portion which only partly surrounds said part of the conductor leaving exposed through the sleeve one face 110 of the conductor which is designed to be attached to the rail, and having another portion which substantially entirely and relatively loosely surrounds the conductor. 115

2. As an article of manufacture, a rail bond comprising a conductor having a terminal part and a terminal sleeve, said sleeve being intimately attached to one face of said terminal part leaving the opposite face of said terminal part exposed and substantially 120 entirely surrounding and relatively loosely attached to the conductor adjacent said terminal part.

3. As an article of manufacture, a rail bond comprising a conductor having a terminal sleeve which loosely and entirely surrounds the conductor at one point and which is intimately attached and only partially

surrounds the conductor at other points, one face or side of the conductor being thus exposed.

4. As an article of manufacture, a rail bond comprising a conductor having a flat terminal portion and a terminal sleeve intimately united to the flat terminal on one

side thereof leaving the opposite side exposed, said sleeve at one point completely but relatively loosely surrounding the conductor.

In testimony whereof, I hereunto affix my signature.

LAWRENCE P. CRECELIUS.
